(57) **CLAIM**

The ornamental design for a headgear appliance mounting with retention clip, as shown and described.

DESCRIPTION

FIG. 1 is a first top and front perspective view of a headgear appliance mounting with retention clip, showing my new design;

FIG. 2 is a first bottom and front perspective view thereof;

FIG. 3 is a second top and front perspective view thereof;

FIG. 4 is a second bottom and front perspective view thereof;

FIG. 5 is a top view thereof;

FIG. 6 is a bottom view thereof;

FIG. 7 is a left side view thereof;

FIG. 8 is a right side view thereof;

FIG. 9 is a front view thereof; and,

FIG. 10 is a rear view thereof.

The broken lines are included for the purpose of illustrating portions of the article and forms no part of the claimed design.
